HENDERSON G. DAVIS, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

BARREL-SEAM AND METHOD OF MAKING THE SAME.

1,266,415.

Specification of Letters Patent. Patented May 14, 1918.

Application filed April 30, 1917. Serial No. 165,400.

To all whom it may concern:

Be it known that I, HENDERSON G. DAVIS, a citizen of the United States of America, residing at Springfield, in the county of 5 Hampden and State of Massachusetts, have invented certain new and useful Improvements in Barrel-Seams and Methods of Making the Same, of which the following is a specification.

10 This invention relates to a method of seaming the heads of containers, such as cans, barrels, and the like, for example, to their bodies and to the improved article resulting from the method.

15 The invention is particularly applicable to the heading of barrels, such as are used to transport oils and the like over long distances under severe conditions. Such barrels need to be tightly seamed to avoid leak-

20 age. The barrels are, however, rather heavy and in transit are subjected to rough handling, being frequently dropped. With the former methods of seaming of which I am aware, the flanges of the barrel shell and its 25 head are interfolded in such a manner that one may move relatively to another, and, when a barrel is dropped, a relative movement between the interfolded flanges may take place, at least sufficiently to allow the

30 fluid in the barrel to work through the seam. Cement and the like has been applied to the flanges during the interfolding operation but after the cement or other sealing means has once hardened, a blow on the seam, such 35 as is administered by dropping the barrel, is sufficient to crack, break, and powder the sealing material and thereby destroy the hitherto sealed seam.

This invention has for its object to provide 40 a method of seaming containers such as heavy oil barrels, whereby the flanges of the head and shell are held together with a locked seam in such a manner that no opportunity is left for relative movement 45 between the head and shell, the construction being characterized in that a seam may be made tight to prevent leakage and in that the jars and jolts received by the barrel will not only not readily loosen the seam but will 50 have a tendency to cause the seam to become more tightly locked than before.

A further object of the invention is to provide the improved barrel which is the product of the method.

Other objects and advantages will appear 55 in the description to follow and will be particularly pointed out in the appended claims.

The invention is disclosed for illustrative purposes in the accompanying drawings, in 60 which:

Figure 1 is an elevational view of a completed barrel made by the method; and

Figs. 2, 3, and 4 are fragmentary sectional views illustrating successive steps in the 65 seaming of the head to the shell of the barrel.

Referring to these drawings in detail, the shell *a* of the barrel in the making is cylindrical in form and at each end is provided with a circumferential flange *b*, which is outwardly turned at right angles to the shell, as shown in Fig. 2. A circular head *c* has a circumferential flange *d* which is adapted to closely fit within the shell *a* and a circumferential flange *e* outwardly turned from 70 flange *d*, which flange *e* is adapted to abut the shell flange *b* and lie parallel therewith. The flange *e* is longer than the flange *b* for a reason later to appear.

The method of joining the head *c* to shell 80 *a* may be accomplished by a variety of mechanical means. For example, the barrel may be supported for rotation by a pair of chucks *f*, which each fit within the depression in head *c*, as shown in Fig. 2. Suitable 85 rolls, such as *g* and *h* (Figs. 3 and 4, respectively) may then be forced successively against the flanges *b* and *e* to produce the seam. The method will be described as carried out by the use of chucks *f* and rolls *g* and *h*. Such preferred mechanical details in carrying out the method is fully described and claimed in my co-pending application Ser. No. 165,399 filed April 30, 1917.

The first step of the method consists in 95 fitting the heads *c* into shell *a* as shown in Fig. 2, and the barrel is then mounted upon the chucks *f*. The roll *g* is then forced against the flanges *e* while the barrel is rotated. Roll *g* is so positioned with relation to the barrel that a shoulder *i* thereon lies in the plane of the outer surface (that to the left in Fig. 2) of the flange *e*. The latter is first engaged by roll *g* and continued movement of the roll toward shell *a* during 105 the rotation of the latter by the chucks gradually bends the flange *e* to the right. Further movement of roll *g* will bend the

flange *b* to the right by engagement with flange *c*. On continued movement of the roll, the end of flange *e* encounters a shoulder *j* on the roll and is thereby bent upwardly around the end of flange *b*, and thereafter in an endwise direction toward the shoulder *i* so that a portion *k* is inserted between flange *b* and shell *a*, as shown in Fig. 3. The flange *e* is made of such length that, when the roll *g* has been moved into abutment with the shell, as shown in Fig. 3, the portion *k* overlaps flange *b* by a distance slightly greater than the thickness of the flange.

To complete the seam, the roll *h* is used, and this roll has shoulders *l* and *m*, which are similar to the shoulders *i* and *j* on roll *g* and arranged to close the joint or seam substantially as shown in Fig. 4 and substantially in the manner to be described. Between the shoulders *l* and *m* is a substantially flat circumferential portion which is adapted to press the flanges *b* and *e*, with the part *k* previously inserted between flange *b* and shell *a*, flatly against the latter. The distance between shoulders *l* and *m* is substantially the same as that between the shoulders *i* and *j*, so that, when roll *h* is applied to the partially formed seam, the flanges interfolded as described cannot move in an endwise direction to any appreciable degree. The flanges being confined between the shoulders *l* and *m*, the roll *h* in flattening the flanges tends to force the ends of flanges *b* and *e* toward shoulder *m*, and this movement of flange *e* tends to force the part *k* in an opposite direction. The part *k* and the end of flange *b*, which it overlaps, thus are subjected to forces which tend to move them in opposite directions to increase the overlap and at the same time roll *h* gradually forces the overlapped end of flange *b* against the part *k*. Thus, the overlapped portions are gradually crushed together and, as they are crushed, the endwise forces act to draw out the part *k* and the overlapped end of flange *b* into wedgelike form. As the roll *h* abuts the shell *a*, the parts are brought into the position shown in Fig. 4, wherein the part *k* is hooked around the pointed end of flange *b* into abutment therewith and into abutment with the shell *a*. It will be apparent from an inspection of Fig. 4 that no opportunity whatever is afforded for relative movement of the flanges under forces applied at the outer end of the seam, as when a barrel is dropped, because the inner ends of flanges *b* and *e* are hooked one on to the other with a relatively slight or comparatively no leverage for one hook to act on the other for separating action.

The important step in this method consists in inserting the part *k* between the flange *b* and the shell and thereafter forcing the portion *k* and the overlapping end of

flange *b* into the form shown. It is particularly desired that the end of flange *b* should form with shell *a* an acute angle and that portion *k* should abut the end of flange *b* and become hooked and locked thereto substantially as shown.

If desired, a slight amount of cement may be placed between the abutting ends of flange *b* and portion *k*. The great pressure applied to force the portion *k* into abutment with the end of flange *b* will spread the cement in a very thin film. The cement thus applied, as a matter of fact, merely fills all the minute irregularities in the abutting surfaces and is not, as formerly, in the form of a layer of marked thickness. The cement, when applied as described, will not crack and cause leakage as heretofore because it is applied by the pressure in an extremely thin film which acts to fill up the smallest of spaces between the abutting metal, which spaces are protected by the metal edges around such spaces. The cement then merely fills minute irregularities of the abutting surfaces.

The important result of the method is to provide a seam wherein the joined parts are locked against relative movement, and this result is obtained by the inturned end *k*, which is hooked around the inclined end surface of flange *b*, and positioned between the latter and shell *a*. The portions *a*, *b*, *d*, and *e*, being jammed together to lie in intimately close contiguous relation cannot move relatively to one another according to their stated relation except in the direction of the axis of the shell, and, due to the inturned and rearwardly inclined portion *k*, the head is prevented from moving in this direction. The seam thus provided is capable of withstanding rough handling without leaking. Assume, for example, that the barrel is dropped endwise, as frequently happens, so that a blow is delivered on the edge *p* (Figs. 1 and 4). The force is transmitted in the direction of the length of the barrel and is transmitted from the rounded end *p* to the rounded end of flange *b*. These two rounded ends have been forced into close abutment and the one cannot move relatively to the other in the direction of the applied force. The latter, therefore, is transmitted to flange *b* which abuts the portion *k* so that the former cannot move relatively to the latter. The end of flange *b* transmits the force to the portion *k*, and the tendency is to turn the latter on the point *q*, as a pivot (Fig. 7). Now, if the surfaces of part *k* and flange *b* abutted along a line perpendicular to the shell *a*, the part *k* might be turned by the described force on point *q* as a pivot but with the described construction this turning movement cannot readily occur. The length of the surface of part *k* which abuts the end of flange *b* is longer than the perpendicular

distance from point *q* to the shell, and the surface is inclined in such a direction that an effort to turn the part *k* on pivot *q* is prevented by the pointed end of part *k* bearing on the shell *a*. The force of flange *b* is exerted on part *k* at an angle such that a part of the force tends to turn the part *k*, as described, and another part of the force acts to force part *k* toward the shell with a tendency to draw the flanges *e* and *b* more tightly together.

It has been my experience that a seam formed as described effectively prevents leakage and is capable of withstanding the jolts and jars encountered in transportation without leaking. This, I believe is due to the peculiar manner of locking the flanges *b* and *e* together by the part *k*, and I have found that repeated blows applied to the seam do not loosen the latter and cause leakage, but on the contrary appear to draw the seam more tightly together. The reasons for this peculiar and advantageous result have been set forth above so far as I understand them.

Thus, I have provided an improved method of heading barrels by a locked seam and an improved barrel resulting from the method which is capable of withstanding rough usage without leaking.

The invention has been described herein for illustrative purposes, but the scope of the invention is defined by the appended claims rather than by the foregoing description.

What I claim is—

1. A barrel or the like comprising a body having a flanged portion bent backwardly flat against the body, and a head having a flanged portion bent backwardly around and flatly against the first-named flange, the flanged portion of the head having an end portion to abut in contiguous relation with and hook around the end of the first-named flanged portion and to abut with said body, all constructed and arranged so that said flanges are held against relative movement by the hooked end portion.

2. A barrel or the like, comprising, a body having a flanged portion bent backwardly flat against the body, and a head having a flanged portion bent backwardly around and flatly against the first-named flange, the end of the first-named flanged portion being arranged to meet the body at an acute angle, the flanged portion of the head having an upturned end to abut and hook around the end of the first-named portion and to abut said body.

3. The method of seaming the head of a barrel or the like to its body which consists in providing both head and body with flanges, in bending both said flanges backwardly toward the body, in bending an end of the head flange around the end of the

body flange and forcing it between the latter and the body so that the end of the flanges overlap for a short distance, and in thereafter applying pressure to the head and body flanges until portions of each have been forced flat against and contiguous with the body with said end of the head flange held between body flange and the body.

4. The method of seaming the head of a barrel or the like to its body which consists in providing both head and body with flanges, in bending both flanges backwardly toward the body, in bending the end of the head flange around the end of the body flange and forcing it endwise between the latter and the body so that the end of the head flange partially overlaps the body flange, in thereafter forcing both flanges flatly against the body, and in confining the flanges against endwise movement during the last-named step, so that the end of the head flange is held between and in abutment with the body and body flange with a hook engagement with the end of the latter.

5. The method of seaming the head of a barrel or the like to its body which consists in providing both head and body with flanges, in bending both flanges backwardly toward the body, in bending the end of the head flange around the end of the body flange and forcing it endwise between the latter and the body so that the end of the head flange partially overlaps the body flange, in thereafter forcing the overlapped portions toward the body until both portions are brought flatly against the body, and in confining the flanges against endwise movement during the last-named step, so that the end of the head flange is held between the overlapped portion of the body flange and the body and so that overlapped ends of the head and body flanges abut along the line which inclined to the body.

6. The method of securing the head of a barrel or the like to its body, which consists in providing both head and body with flanges, in bending both flanges backwardly toward the body, in bending the end of the head flange around the end of the body flange and forcing it endwise between the latter and the body until the ends of the head and body flanges overlap for a short distance, in thereafter applying pressure both normally and endwise to the overlapped portions until both of the latter are forced into the same plane, flatly against and contiguous with the body, so that the end of the head flange is held between and in abutment with the body and body flange.

7. An article of manufacture, comprising, a member having a flanged portion bent backwardly against and contiguous with the member, a second member having a flanged portion bent backwardly around the first-named flange in contiguous relation there-

1 with, the flanged portion of the second member having an end portion to abut in contiguous relation with and hook around the end of the first-named flanged portion and 5 to abut with the first-named member, all constructed and arranged so that said flanged portions are held against relative movement by the hooked end portion.

8. The method of securing members by 10 seaming, which consists in providing both members with flanges of unequal length and in disposing said flanges in contiguous relation, in bending both flanges backwardly to-

ward one member, in bending the end of the longer flange around the end of the shorter 15 flange and forcing it endwise between the latter and last-named member until the ends of the flanges overlap for a short distance, in thereafter applying pressure both normally and endwise to the overlapped portions until both of the latter are forced into contiguous 20 relation with the last-named member so that the end of the longer flange is held between and in abutment with the latter and the shorter flange.

HENDERSON G. DAVIS.

Correction in Letters Patent No. 1,266,415.

It is hereby certified that in Letters Patent No. 1,266,415, granted May 14, 1918, upon the application of Henderson G. Davis, of Springfield, Massachusetts, for an improvement in "Barrel-Seams and Methods of Making the Same," an error appears in the printed specification requiring correction as follows: Page 3, claim 5, strike out line 108 and insert the words *along a line which is inclined to the body*; and that the said Letters Patent should be read with this correction therein that the same may conform to the record of the case in the Patent Office.

Signed and sealed this 4th day of June, A. D., 1918.

[SEAL.]

F. W. H. CLAY,

Acting Commissioner of Patents.

Cl. 113—116.
